UNITED STATES PATENT OFFICE.

ALFRED H. MCCOLLUM, OF BLOOMSBURG, PENNSYLVANIA, ASSIGNOR TO THE MAGGIE CARPET CO., OF BLOOMSBURG, PENNSYLVANIA, A CORPORATION OF PENNSYLVANIA.

BLOCK-PRINTING MACHINE.

Application filed April 13, 1928. Serial No. 269,770.

This invention relates to improvements in block printing machines, and the principal object of the invention is to provide a machine of this type adapted for printing woven pile fabrics and in general any textile fabric having selvaged edges and on which the printed design is to be carried to said edges.

More particularly, the invention resides in a novel arrangement of parts whereby the elements which feed the fabric through the machine are so relatively arranged with respect to at least one of the printing blocks that the former does not interfere with the operation of the latter in printing to the extreme edge of the fabric.

Another object of the invention is to provide a printing machine of the stated type which shall be further adapted to the printing of textile fabrics by inclusion of suitable teasing means arranged to remove from the fabric such loose material as may interfere with the efficient operation of the printing blocks.

In the attached drawings:

Figure 1 is a more or less diagrammatic longitudinal section through a portion of a printing machine made in accordance with my invention;

Fig. 2 is an enlarged section of a portion of the mechanism shown in Fig. 1;

Fig. 3 is a transverse section on the line 3—3, Fig. 2;

Figs. 4 and 5 are fragmentary transverse sectional views on the lines 4—4 and 5—5, respectively, Fig. 2; and

Fig. 6 is a view in perspective of a section of the table illustrating a detail of construction.

Referring to the drawings, the machine may comprise the usual frame 1 supporting a table 2 over which the fabric is fed from a roll 3 mounted in the usual manner at one end of the machine. The machine further comprises a series of printing blocks extending longitudinally of the machine two of which are shown in the drawings and indicated by the reference numerals 4 and 5 respectively. These blocks which extend transversely across the table 2 are reciprocated vertically by well known means to bring them periodically into contact with the surface of the fabric fed, as hereinafter described, along the table 2.

Intermediate or adjacent the printing blocks and in accordance with the usual practice are located suitable receptacles 6 for the dye or other substance constituting the printing medium, and operatively associated therewith a roll 7 which is adapted for distributing the said medium over the faces of the blocks. To accomplish this, the receptacles, as is customary, may be mounted upon wheels 8 which operate on suitable tracks or in guides at the opposite sides of the machine, and means is provided whereby the receptacles are periodically drawn under the blocks so that the distributing roll 7 is brought into contact with the working faces of the latter. In the present instance, I have illustrated the receptacles 6 connected through a rod 9 with an arm 10 on a shaft 11, this arm being oscillated in any desired manner from the operating mechanism of the machine and in timed relation with the movement of the printing blocks.

As a means for advancing the fabric along the table 2, I provide at each side of the machine in the present instance an endless belt or chain 12 which at the forward end of the machine operates around a pulley 13, this belt having projecting from its outer face a longitudinal series of pins or spikes 14 adapted to penetrate the fabric from the under side and at the longitudinal edges thereof whereby, the belt moving as indicated, the fabric is dragged along the table under the printing blocks.

It has been customary in machines of this type used in the printing of oilcloth and similar materials to print the desired design short of the lateral edges of the material leaving an unprinted strip at each edge in which the pins 14 take effect, and which is eventually trimmed off. In printing textile fabrics having selvaged edges, this method of printing is manifestly inadequate by reason of the fact that the fabric cannot be trimmed and by reason further that the border design must extend in most instances to the extreme edge of the fabric. In the present machine, therefore, I provide means whereby the fabric-moving elements 12 may operate without interfering with the operation of at least one of the printing blocks in printing the fabric to the extreme side edges. As illustrated in the drawings, the pulleys 13 around

which the belts 12 operate at the forward end of the machine are so arranged that the upper run of the belt during an initial stage extends in a plane below the table 2 and at 5 an upward inclination to the latter so that the belt at a predetermined point moves into the plane of the table bringing the pins 14 into contact with the under surface of the fabric 16, as shown in Fig. 2, whereby the 10 pins are caused to enter the fabric and the latter is carried along the table in the usual manner. Intermediate the forward end of the machine and the point where the belt 12 comes into operative relation with the fabric, 15 I locate the printing block 4, which is thereby afforded an unobstructed operation from one transverse side of the table 2 to the other, and is thereby adapted to print to the extreme side edges of the fabric. Where a 20 border design is to be impressed upon the fabric, the block 4 will carry this design, and its function primarily is that of a border block.

It will be noted by reference to Figs. 2 25 and 6 that the table 2 is provided at the opposite edges with an inclined slot 15 extending inwardly from the edges which provides passage for the belt 12 in its travel to the upper plane of the table, it being understood that in the remainder of its upper run the belt is supported on the surface of the table, and as clearly illustrated in Fig. 6, the edge 30 portions of the table upon which the belts run are depressed to an extent corresponding to the thickness of the belt.

Following the printing of the border by the block 4, the remaining blocks represented for example by the block 5, the effective 35 printing faces of which are shorter transversely of the machine than the block 4, print the interior design between the borders in the usual manner and are unobstructed by the belt 12 or the pins 14 which penetrate the edges of the fabric.

45 In the printing of textile fabrics, and particularly of the pile fabrics which are ordinarily employed in the manufacture of floor coverings, I have found that there is a tendency, particularly with certain types of printing block, for the loose lint and threads in the fabric to stick to and accumulate on the faces of the printing blocks eventually materially interfering with their normal operation. I have discovered that this undesirable effect may be eliminated to a large 55 degree by means of a suitable teasing device operating on the fabric immediately in advance of the printing blocks and adapted to remove all loose substances from the fabric.

60 Such a device is illustrated in the drawings in which a hollow manifold member 16 extending transversely over the table 2 is connected at one end with a suitable fan or exhauster (not shown) and which also com-

municates with a plurality of hoods 17 which 65 extend downwardly to a point closely adjacent the upper surface of the fabric as it moves along the table. In the lower parts of the hoods 17 is a rotary brush 18 on a shaft 19 journaled in the present instance 70 in said hoods themselves and having at one end a pulley 20 by means of which the shaft is operatively connected with a suitable source of power, as for example a belt 21 operating from the shaft 22 of the machine. 75 This brush is in direct contact with the fabric as illustrated in Fig. 2 and is preferably rotated in a direction opposed to the movement of the fabric on the table. Under these circumstances, all the loose materials in the 80 carpet are brushed off and are drawn by suction into the manifold 16 and through to a suitable discharge. It will be noted that the manifold 16 has at its outer closed end a detachable cap 23 providing access to 85 the interior of the manifold for cleaning purposes.

By means of the foregoing mechanism, I have provided a block-printing machine which is adapted for the printing of textile 90 fabrics. It will be understood that the machine may vary largely as to the details of construction without departure from the essential features of the invention as defined in the appended claims. 95

I claim:

1. In a block printing machine, the combination with a support for the printed article, of printing blocks operatively associated with said support, means adapted to 100 engage the side edges of said article for feeding it over the support, means for relatively moving the support and the blocks whereby the latter are caused to impress a marking on said article, and means for rendering said feeding means locally inoperative to engage the article whereby at least one of said blocks is enabled to make an impression to the extreme side edges of the article. 105

2. In a block printing machine, the combination with a table support for the printed article, of means adapted to engage the side edges of the article for advancing the latter on the table, printing blocks for impressing a design on the article, at least one of said blocks being adapted to make an impression to the extreme side edges of the article, and means for rendering the advancing means locally inoperative to engage the article to leave the article unobstructed for operation 110 of the last-named block. 115

3. In a block printing machine, the combination with a printing platen, of printing blocks operatively associated with the platen, means for advancing an article on the platen, 120 and for holding the article for operation of the printing blocks in impressing a design thereon, and means for rendering said ad-

vancing and holding means locally inoperative to afford a completely unobstructed area extending from one side edge to the other side edge of the article for operation of at least one of said blocks.

4. In a block printing machine, the combination with a platen support for the printed article, of an endless conveyer element the upper run of which is adapted to move at the sides of said platen, said conveyer element having outwardly projecting pins adapted to pierce the printed article on the platen, and said platen extending at one end beyond said conveyer, and a plurality of printing blocks for impressing a design on the article, at least one of said blocks being operative with that portion of the platen extending beyond the conveyer whereby it is

afforded an unobstructed operation to the extreme edges of the article. 20

5. In a block printing machine, the combination with a platen support for the printed article, of a plurality of printing blocks operatively associated with said platen, means for actuating said blocks to impress a design upon an article on the platen, and means for advancing an article from one end of the platen towards the other including article-gripping elements adapted to engage the article at a point rearwardly of at least one of said printing blocks whereby the latter is afforded an unobstructed operation from one side to the other of said article. 25 30

ALFRED F. McCOLLUM.
